(57) **CLAIM**

I claim the ornamental design for a hood scoop for a high mobility multipurpose wheeled vehicle, as shown and described.

DESCRIPTION

FIG. 1 is a front perspective view of a hood scoop for a high mobility multipurpose wheeled vehicle, showing my new design, shown in its position of use;

FIG. 2 is a side view thereof, shown in its position of use;

FIG. 3 is a rear perspective view thereof;

FIG. 4 is a side view thereof; and,

FIG. 5 is a top plan view thereof.

The hood scoop for a high mobility multipurpose wheeled vehicle is shown on an enlarged scale in FIGS. 3-5.

The broken line showing of environment is for illustrative purposes only and forms no part of the claimed design.
